Peter Louis

UNITED STATES PATENT OFFICE.

PETER LOUIS, OF NEW YORK, N. Y., ASSIGNOR TO HIMSELF, AND HIRAM WANDIEL, OF RICHMOND COUNTY, NEW YORK.

VALVE-GEAR OF STEAM-ENGINES.

Specification of Letters Patent No. 26,275, dated November 29, 1859.

To all whom it may concern:

Be it known that I, PETER LOUIS, of the city, county, and State of New York, have invented certain new and useful Improvements in Valve-Gear for Steam-Engines; and I do hereby declare that the following is a full, clear, and exact description of the same, reference being had to the accompanying drawings, forming a part of this specification, in which—

Figure 1, is a front elevation of the side pipes, valve chest and valve gear of a beam engine. Fig. 2, is a vertical section at right angles to Fig. 1, in the plane indicated by the line X, X. Fig. 3, is a vertical section in the plane indicated by the line Y, Y, of Fig. 1.

Similar letters of reference indicate corresponding parts in the several figures.

My invention relates to the direct application of steam to operate the valves of steam engines, and is more especially intended for use in beam engines or other engines with upright cylinders, having puppet valves, but it may be applied to any engines whose valves have a vertical motion.

It consists in a novel mode of applying an auxiliary steam cylinder and pistons in combination with the valves of the main engine to effect a quick opening and control the closing of said valves. And it further consists in certain means of retaining the eduction valves of the main engine in an open condition after the cutting off takes place.

To enable others skilled in the art to make and use my invention I will proceed to describe its construction and operation.

A, and B, are upper and lower valve chests and C, C, side pipes, such as are common to upright puppet valve engines, the valve chests containing the usual system of balanced puppet valves.

The induction valves I, I', are exhibited in Fig. 3, and the eduction valves E, E', in Fig. 2, but Fig. 1, though it exhibits none of the valves, exhibits the stems i, i', of both the induction valves and the stems e, e', of both eduction valves. The stems i, and e, of the two upper valves pass through stuffing boxes in the bottom of the valve chest A, and the stems i', and e', of the lower valves, through stuffing boxes in the top of the valve chest B. The above described parts all belong to the main engine.

D, is the auxiliary steam cylinder containing the pistons F, and F', upon which the steam operates to open the valves of the main engine, said cylinder being very small in proportion to the main engine cylinder 60 and having a transverse partition g, (Fig. 3) at the middle of its length and having one piston above and the other below said partition, the rod e, of the upper piston F, passing through a stuffing box in its upper 65 end and the rod e', of the lower one through a stuffing box in the lower end. This cylinder D, is secured in an upright position to a frame G, which is bolted to the side pipes C, C. It is furnished with a valve chest H, containing a short slide valve T, and a similar arrangement of ports h, h', j, to those commonly employed in small slide valve steam engines, the port h, communicating with the bottom of the upper compartment of the said cylinder, the port h', with the bottom of the lower compartment of the said cylinder and the port j, with an exhaust pipe k, which may open into the atmosphere or into the condenser of the 80 main engine. The steam chest H, is supplied with steam from the boiler by a pipe l, which connects with a small valve box m, at the back of the steam chest H, said valve box being fitted with a sliding throttle and stop valve n, whose stem n', is connected with a hand lever p. The steam pipe l, is fitted with a plunger valve q, and the exhaust pipe k, with a similar valve r, the said valves being capable of adjustment by 90 means not necessary to be here described to control the admission and escape of steam. The slide valve T, has its stem u, connected with the arm w, of a horizontal rockshaft J, which is arranged to work in bearings 95 v, v, secured to the side pipes C, C, and whose arm w*, connects with the rod K*, of an eccentric K, on the main or crank shaft of the main engine or any other shaft provided for the purpose, deriving motion 100 from such main shaft, as will be presently described.

The rock-shaft J, is furnished with a hand lever L, to enable the valve T, to be worked by hand. The cylinder D, with its pistons and valves and valve gear may be considered as an auxiliary engine. The upper piston rod e, is furnished with a cross-head a, and the lower one with a cross-head a', each of said cross-heads being secured 110

firmly to its respective piston-rod. The upper cross-head *a*, has connected with it the stem *i*, of the upper induction valve *I*, and the stem *e'*, of the lower eduction valve *E'*, and the lower cross-head *a'*, has attached to it the stem *i'*, of the lower induction valve *I'*, and the stem *e*, of the upper eduction valve *E*.

The connection of the stem *e*, with the cross head *a'*, is made by means of a vertical rod *b*, which is rigidly attached to the said stem by an arm *b**, and hence the two stems *e*, *e'*, are prevented interfering with each other. The stems *i*, *i'*, are furnished with fast collars *f*, *f'*, above their respective cross heads and the stem *e'*, and rod *b*, are furnished with similar collars *z*, *z'*, against which the cross heads press upward to lift the valves of the main engine when the pistons *F*, *F'*, of the auxiliary engine are raised by the pressure of steam below them in the cylinder *D*; but the said stems and rod are so fitted to their respective cross-heads that the latter are capable of sliding on the said stems and rod below the said collars. The object of such mode of fitting the stems to the cross heads is to permit the eduction valves of the main engine to be opened a little before the induction valves thereof, and to permit the cross heads to descend with the said induction valves to cut off the steam while the said eduction valves remain open. Springs 4, 4', are applied between the cross heads and the collars *f*, *f'*, of the induction valve stems of the main engine to enable the eduction valves to be first opened, the induction valves not commencing to open till the elasticity of the spring is overcome by the upward pressure of the cross heads.

N, is a horizontal rock-shaft arranged to work in bearings bolted to the backs of the side pipes, said rockshaft being furnished with two toes *O*, *O'*, which are arranged under arms *P*, *P'*, the former of which is fast upon the rod *b*, and the latter upon the stem *e'*. The said rock shaft is also furnished with an arm *Q*, by which it is connected with the eccentric rod *K**, and caused to derive a rocking motion from the eccentric *K*, coinciding with the rocking motion of the rockshaft *J*. The toes *O*, *O'*, are so arranged that they follow the arms *P*, *P'*, and their respective rod *b*, and valve stem *e'*, are raised by their respective cross heads, for the purpose of being ready to receive the said arms and support the said rod and stem and so keep the eduction valves of the main engine open to the end of the stroke of its piston notwithstanding the descent of the crossheads to permit the closing of its induction valves to cut off the steam.

The operation of the valve gear is as follows: The slide valve *T*, of the auxiliary

engine is worked by the eccentric *K*, in the same manner as the slide valve of an ordinary steam engine admitting steam to each compartment of the cylinder *D*, in turn and permitting the exhaust from the opposite end once during every revolution of the crank shaft of the engine. It may be proper here to remark that the valve *T*, should be a double lap valve so that it may be capable of cutting off steam early in the upward stroke of either of the pistons *F*, *F'*, that the steam may be allowed to act expansively upon said pistons. When steam is admitted to the upper compartment of the said cylinder *D*, it raises the piston *F*, and with it the upper induction valve *I*, and lower eduction valve *E'*, of the main engine, effecting a very quick opening of said valves and admitting steam to the upper end of the cylinder of the said engine and permitting its exhaust from the lower end thereof. When the steam has been cut off from the passage *h*, by the movement of the slide valve *T*, and the exhaust permitted from the upper compartment of the cylinder *D*, the piston *F*, descends with the valve *I*, to cut off the steam from the main engine, but the descent of the said piston is so much checked by the slowness of the exhaust resulting from the contraction of the passage of the exhaust pipe *k*, by the valve *r*, that the valve *I*, is lowered so gradually as to prevent its slamming. The eduction valve *E'*, does not descend with the piston *F*, the toe not permitting it to close till the stroke of the main engine piston is terminated. When steam is admitted to the lower compartment of the cylinder *D*, the piston *F'*, operates in the same manner as above described with reference to *F*, and produces the operation of the valves *I'*, and *E*, in the same manner as above described with reference to *I*, and *E'*. The cutting off of the steam from the main engine by the valves *I*, and *I'*, is made to take place earlier or later in the stroke of the engine piston by adjusting the valve *r*, to give a more or less free exhaust. This may be also varied by giving the slide valve *T*, more or less movement to make it cut off steam sooner or later in the stroke of the small pistons *F*, *F'*, and provision is made for this latter mode of variation by constructing the arm *w*, of the rockshaft *J*, to screw through the said rockshaft as represented in the drawing or otherwise making provision for varying the effective length of the said arm.

The valve *T*, may be operated by means of a cam instead of an eccentric and by that means the steam may be cut off in the cylinder *D*, at an earlier point in the stroke of the engine piston, and so an earlier cutting-off of the steam by the valves *I*, *I'*, may be obtained.

The heads of the cylinder *D*, may each

have an opening with a pipe attached to communicate with the condenser of the main engine, by which means the pistons F, F', may be operated to open the valves with less steam and the cushioning effect of the steam in D, is aided to check the descent of the said pistons. When such connection with the condenser is not made, no stuffing boxes are required in the heads of the cylinder D, but simply guides for the piston rods c, c'.

I do not claim broadly effecting the operation of the valves of steam engines by the direct application of steam but

15 What I claim as my invention and desire to secure by Letters Patent, is—

1. The auxiliary cylinder D, having a partition g, and arrangement of steam and exhaust passages substantially as described, 20 and fitted with a valve T, or its equivalent and with two pistons F, F', on opposite sides of its partition, applied substantially as described in combination with the induction and eduction valves and the shaft of

the main engine so that each of said pistons 25 acted upon by steam admitted to its compartment of the auxiliary cylinder by the valve T, or its equivalent serves to open one induction and the opposite eduction valve of the main engine at the proper time 30 substantially as herein described.

2. In combination with the auxiliary cylinder D, and its pistons applied and operating as described to open the induction and eduction valves of the main engine, I claim 35 the employment of the rockshaft N, and its toes O, O', so applied in combination with the said eduction valves that while they permit the said valves to be opened by the action of the steam on the pistons of the 40 auxiliary cylinder they keep the said valves open as long as may be desired substantially as herein described.

PETER LOUIS.
